his Attorney.

UNITED STATES PATENT OFFICE.

VICTOR C. ARMSTRONG, OF HACKENSACK, NEW JERSEY, ASSIGNOR TO THE RAIL JOINT COMPANY, OF NEW YORK, N. Y., A CORPORATION OF NEW YORK.

WEAR COMPENSATING UNIT FOR RAIL JOINTS.

Application filed December 7, 1926. Serial No. 153,144.

This invention relates to an improvement in rail joint construction and has for its chief object the provision of a novel wear compensating unit possessing special utility 5 as a means for reclaiming old or worn rail joints whereby rail joint bars which have become worn by the "working" of the rail in a joint can be utilized again with either old rail or new rail.

10 To that end the present invention contemplates a novel construction of wear compensating unit in the form of a metallic shim of such a form and construction as to compensate for wear at the top of the joint bar as 15 well as at the underside of the rail heads of the rail ends within the joint without the necessity of grinding off or otherwise removing the burr, fin, or projection of metal which is usually produced at the medial portion 20 of the top of the bar by the wearing down of the same while in service. In the performance of that useful and desirable function the present invention is intended as an improvement upon the two-part or divided shim construction of my Patent 1,615,- 25 500 granted January 25, 1927.

While the invention is necessarily susceptible of structural modifications without departing from the spirit or scope of the invention, a preferred and practical embodiment 30 is shown in the accompanying drawings, in which:—

Figure 1 is a perspective view of a worn rail joint which has been restored to form 35 and fit by the use of the novel shim construction contemplated by the present invention.

Figure 2 is a side elevation of the joint shown in Fig. 1 with the joint bar removed to illustrate more clearly the position and 40 form of the shim.

Figure 3 is a detail perspective view of the novel shim construction.

Figure 4 is a vertical cross-sectional view 45 through the shim at its central portion indicating by dotted lines the relation thereto of the worn head of the joint bar.

Figure 5 is a detail elevational view showing a modified form of the shim, indicating how the central clearance space can be provided for in another way.

The improved shim designated generally A is preferably made of a grade and specification of steel capable of withstanding the pressure and wear of service and is usually of an angle formation having the depending

flange or apron 1 adapted to lie between the underside of the head of the joint bar B and the rail web and the upper wear flange 2 which is adapted to occupy a position between the head of the bar and the undersides of the rail heads. One of these shims is adapted to be used at each side of the joint and each shim occupies the central or medial part of the rail joint, that is, the part of the joint within which the greatest wear has occurred, and in the application of a shim to a joint it is only necessary first to loosen the bolts so that the joint bars may be eased off from the rail ends, after which the shim is inserted in place between the head of the bar and the adjoining rail ends. Then by re-tightening the bolts the joint is restored to proper form and fit so as to satisfactorily hold the rails R in proper alignment as to surface and gauge.

Each shim or angle plate A is of a double taper formation. That is to say, the shim is tapered from its center toward both ends so that the thickest part of the shim lies at the center of the joint where the greatest wear has taken place, while both ends of the shim are thinned down, preferably to a wafer thickness so with the shim in place the joint bar when tightened against the rails will take a satisfactory head fishing throughout from end to end. In addition to the double tapered formation of the shim or angle plate A the shim body is provided in its central part with a clearance space 3 which is formed in the upper wear flange 2 in a location to receive, and provide clearance for, the upstanding burr, fin or projection of metal, marked X, at the head of the worn bar, thereby obviating the expense and time that would be required to trim, grind or hammer down such burr, fin or projection of metal, as would be necessary if the worn bar was to be reused on an old or new rail without shims of the character described and claimed herein.

In carrying out the invention it will be obvious that the clearance space 3 may be provided in different ways. For instance as shown in Figures 1 to 4 of the drawings provision is made for this clearance space by notching or cutting out the metal in the central part of the upper wear flange 2, but in some cases it would be entirely practical to provide the necessary clearance for the projection of metal on the head of the worn

bar by grooving or channeling as at 3^a the underside of the upper wear flange 2 as suggested by the modification of Figure 5 of the drawings. It will however be obvious that other structural modifications, to provide clearance spaces of the kind necessary for the purposes of this invention, can be resorted to without departing from the scope of the invention or sacrificing any of its principles.

I claim:

1. A wear compensating unit for rail joints consisting of a metallic shim tapering in thickness toward both ends, said shim having at an intermediate point a clearance space for metal projections on the joint bar.

2. A wear compensating unit for rail

joints consisting of a metallic shim of angular cross-section and tapering in thickness toward both ends, said shim having at an intermediate point a clearance space for metal projections on the joint bar.

3. A wear compensating unit for rail joints comprising a metallic shim of angular cross-section and tapering in thickness toward both ends, said metallic shim having in its upper flange a centrally located notch or cut-away portion forming a clearance space for projections of metal on the joint bar head.

In testimony whereof I hereunto affix my signature.

VICTOR C. ARMSTRONG.
